UNITED STATES PATENT OFFICE

HARRY R. PARSHALL, OF CHICAGO, ILLINOIS, ASSIGNOR TO AUTOMATIC ELECTRIC INC., OF CHICAGO, ILLINOIS, A CORPORATION OF DELAWARE

AUTOMATIC TELEPHONE SYSTEM

Application filed October 23, 1926. Serial No. 143,558.

This invention relates to telephone systems in general, but more particularly to small automatic telephone systems.

In small systems of this type it is customary that all of the special service trunks, for instance, information, complaint, intercepting, and inspectors' trunks, terminate in a single switchboard on account of the fact that there are not sufficient calls of this nature to warrant separate positions for each type of service. A single operator or attendant is capable of handling all the calls coming into such a switchboard. The invention relates to equipment used by the operator for handling calls coming in at the switchboard and more particularly to an improved single plug ended cord circuit arranged for extending calls either through the cord circuit from a calling to a called subscriber, or direct from the operator to a called subscriber when the operator is the calling party.

The various features of the invention will be described in detail in the following specification in connection with the explanation of the operation of the various circuits which are described with the aid of the accompanying drawings.

Referring now to the drawing, there is shown by means of the usual circuit diagram a trunk circuit TC, an improved single plug ended cord circuit CC, an operator's headset O, and a rotary lineswitch LS for extending calls.

The trunk circuit TC and similar trunk circuits extend from the banks of automatic Strowger selector switches in the regular trunking arrangement and terminate at the switchboard in jacks such as jack J. A trunk circuit of this type may be used for handling complaint or information calls, or may be used as an inspector's trunk.

The cord circuit CC at the operator's position terminates in one end in the plug P and at the other end in the conductors 45 and 46 which extend through an intermediate distributing frame to a rotary lineswitch LS. In the cord circuit CC there is provided a two-way, locking, lever type key TK and DK used for talking when operated in one direction and for dialing when operated in the op-

posite direction. The key as shown is in normal or neutral position. A number of relays are also shown in this cord circuit, the circuits of which in combination with the talking and dialing keys permit special operating features to be performed.

The operator's headset O shown directly above the cord circuit is provided with a calling device CD and the usual instrumentalities for permitting her to converse with either the calling or called subscriber.

The lineswitch LS is located in the automatic switchroom and is of the well known rotary type, in which the wipers have no normal position and remain in the position last used. The rotary lineswitch LS has access to selector switches in the regular trunking arrangement of the automatic exchange thereby enabling the operator to extend a connection or complete a connection to any one of the subscribers in the automatic exchange.

With this general description of the drawings in mind, the operation of the circuits may now be explained in detail. For this purpose, it will first be assumed that an inspector is calling in on the trunk circuit and that it becomes necessary for the operator to extend the call through the regular train of switches to a subscriber's line. The calling party dials the proper digits to trunk the call through the automatic switches to an idle trunk circuit, which we will assume is the trunk circuit TC. When the selector seizes the trunk circuit TC, which it does over conductors 1, 2, and 3, relay 5 energizes over the following circuit: from ground through the upper winding of relay 5, armature 13 and its resting contact, conductor 1, through the calling party's loop, conductor 3, resting contact of armature 14 and said armature, and lower winding of relay 5 to battery. Relay 5, upon energizing, closes at armature 10 and its working contact a circuit for lighting the call lamp L; at armature 11 and its working contact connects the ring back tone machine RB to the calling line in the well known manner; and at armature 12 and its working contact closes a circuit for energizing slow acting relay 4. Relay 4, upon energizing, prepares a locking circuit for relay 7 at arma-

ture 9 and its working contact; and at armature 8 and its working contact connects ground to the release trunk conductor 2, thereby making the trunk circuit TC busy to other selectors having access thereto and providing a holding circuit for the operated switches.

The operator at the switchboard perceiving the lighted condition of the lamp L inserts the plug P of the cord circuit CC into the jack J of the trunk circuit TC. Responsive to the insertion of the plug P into the jack J, a circuit is closed for energizing relays 6 and 7 of the trunk circuit TC and the relay 20 of the cord circuit CC in series, as follows: from ground by way of armature 40 and its resting contact, resting contact controlled by spring 33 of the dial key DK and said spring, relay 20, sleeve conductor of plug P, sleeve of jack J, spring 19 and its working contact, upper winding of relay 7, and winding of relay 6 to battery. Relay 6, upon energizing over the above traced circuit, opens at armatures 13 and 14 the circuit for relay 5; and at armature 15 and its working contact maintains the slow acting relay 4 energized. Relay 7, upon energizing, at armature 18 and its resting contact disconnects the ring back tone machine RB; at armature 17 closes a locking circuit for itself, and at armature 16 extinguishes lamp L and prepares a circuit for lamp L'. Relay 5, upon deenergizing, at armature 12 opens the original energizing circuit of relay 4, which however is now maintained energized from ground at armature 15. It may be mentioned here, that the disconnection of the ring back tone indicates to the calling party that the operator has answered.

In the cord circuit CC relay 20, upon energizing, disconnects resistance 35 and battery from armature 36, and at armature 37 opens a point in the circuit of relay 21. It will be noted that the relay 22 is short circuited by the dial key DK at springs 33 and its resting contact. Relay 22 is prevented from operating by this shunt circuit so as not to initiate the operation of the lineswitch LS. With this arrangement the lineswitch is prevented from operating and does not therefore tie up a trunk at this time.

After the insertion of plug P into the jack J, the operator or attendant at the switchboard will operate the talk key TK and converse with the calling party. By the operation of the talk key TK, the operator's headset O is connected directly across the trunk. It will be observed that the retardation coil 25 furnishes talking battery for the calling party through resting contacts on armatures 39 and 42.

The operator or attendant, upon ascertaining that it is desirable to connect the calling party with an automatic subscriber in the exchange, restores the talk key TK and

operates the dial key DK. Responsive to the operation of dial key DK, spring 33 and its resting contact are separated thereby rendering effective a circuit for operating relay 22 in series with the sleeve relay 20. At the dial key springs 32 and 34, the cord circuit is divided into two sections and the operator's calling device CD is bridged across the talking conductors of the outgoing section. Relay 22, upon energizing, over the above traced circuit closes at armature 40 and its working contact a circuit for the electropolarized relay 23 (not operated at this time), a circuit for lighting supervisory lamp L'; and at armature 41 and its working contact prepares a bridge across the outgoing trunk which bridge includes the retardation coil 24 and the upper winding of the electropolarized relay 23. Relay 22, at armatures 39 and 42 and their resting contacts disconnects the battery feed relay 25 and at its working contacts connects the calling device directly across the trunk conductors 45 and 46. A circuit may now be traced for operating relay 27 of the lineswitch LS as follows: from ground, resting contact of armature 49 and said armature, conductor 46, working contact of armature 42 and said armature, working contact of the dial key DK controlled by springs 34 and said spring, the impulse springs of the calling device CD, spring 32 of the calling device key DK and its working contact, armature 39 and its working contact, conductor 45, armature 47 and its resting contact, and winding of relay 27 to battery. Relay 27 energizes and closes a circuit for the switching relay 26 and the stepping magnet 28 in series at armature 51, and connects the wiper 54 to the junctions of the switching relay 26 and stepping magnet 28 at armature 50.

The operation of the lineswitch LS depends upon the busy or idle condition of the trunk upon which the lineswitch wipers are resting. In case the trunk upon which the wipers of the lineswitch are resting is idle, switching relay 26 energizes immediately. Assuming the trunk to be busy, switching relay 26 is short circuited from ground at the test wiper 54 and does not energize. The wipers 53, 54, and 55, are rotated step-by-step in a buzzer like manner by the action of the stepping magnet 28, which operates from ground on the busy test contacts encountered by the test wiper 54. When an idle trunk is reached, which will be assumed to be the trunk comprising conductors 56, 57, and 58, the stepping magnet 28 will stop its stepping operation, and relay 26, being no longer short circuited, energizes in series with stepping magnet 28. Stepping magnet 28 does not operate at this time on account of the high resistance of the switching relay 26. Relay 26, upon energizing, opens the circuit of the relay 27 at armatures 47 and 120 125 130 135 140 145 150 155 160 165 170 175 180 185 190 195 200 205 210 215 220 225 230 235 240 245 250 255 260 265 49 and at armature 48 prepares a holding circuit for itself. At armatures 47 and 49, relay 26 disconnects the line conductors 45 and 46 from the winding of the line relay 27 and ground, and extends them by way of wipers 53 and 55, conductors 56 and 58 to the line relay of the selector in which the selected trunk terminates. The line and release relays of the selector energize in known manner and the release relay connects ground to conductor 57, thereby completing the holding circuit for relay 26 before relay 27 falls back.

The operator may now dial the digits of the desired number. Responsive to dialing, the selector and other automatic switches necessary to extend the connection to the desired line are operated in the well known manner. During the operation of the calling device CD the shunt spring 62 engages its working contact thereby causing the operation of relay 60 in the operator's circuit. The operation of relay 60 causes the circuit to the operator's headset to be opened at armature 61 and its resting contact. Although this operation is of no utility at this time, it is essential when the operator dials on other trunk circuits (not shown) with which the headset is intended to be used.

30 When the operator has finished dialling, she restores the dialling key DK. Since relay 22 is now energized, the normal short circuit around this relay is not again closed, due to the open contact at armature 40.

35 When the dial key is restored the calling device bridge is replaced by the bridge previously mentioned, including relays 23 and 24. The electropolarized relay 23 is not energized because the flow of current through 40 said relay is in the wrong direction.

When the called party answers, responsive to ringing current applied by the connector switch, which is the last switch in the train operated by the operator, the back bridge relay in the connector switch energizes and reverses the direction of current flow in conductors 45 and 46 in the regular way. The flow of current is now in the proper direction to energize relay 23.

50 At armature 43, relay 23 opens the circuit of the supervisory lamp L^2 , thereby notifying the operator that the called party has answered. The calling and called parties may now converse with each other as desired.

55 Upon the termination of conversation and responsive to the hanging up of the receiver by the called party the back bridge relay of the connector releases and reverses the current flow over conductors 56 and 58 so that 60 the electropolarized relay 23 deenergizes. Relay 23, upon deenergizing, again closes the circuit for supervisory lamp L^2 at armature 43 and its resting contact. The operator, upon observing the lighted condition of lamp 65 L^2 , removes the plug P from the jack J there-

by opening the circuit of relays 20 and 22. Relay 22, upon deenergizing, opens the circuit of the supervisory lamp L^2 , and at its other armatures 39, 41, and 42 opens the bridge from across the trunk conductors 45 and 46. The removal of the bridge across the trunk conductors 45 and 46 results in the release of the line switch LS and the automatic switches used in extending the call. When relay 20 deenergizes, the cord circuit 70 CC is available for extending other calls.

Responsive to the removal of the plug P from the jack J, the circuit of relays 6 and 7 is opened. Relay 6 deenergizes but relay 7 is maintained energized over armature 17 and its working contact. Assuming that the calling party has hung up his receiver, relay 4 deenergizes after an interval responsive to the opening of its circuit at armature 15. When relay 4 deenergizes, said relay opens 80 at armature 9 and its working contact the locking circuit of relay 7 whereupon relay 7 deenergizes.

Assuming, however, that the calling party for some reason does not replace his receiver 90 and wishes to again talk with the operator, under such conditions relay 5 energizes over the calling party's loop as soon as relay 6 deenergizes. Relay 5, upon reenergizing, closes at armature 12 and its working contact the 95 circuit for maintaining slow acting relay 4 energized; and at armature 10 and its working contact closes a circuit for lighting the hold lamp L' as follows: from ground working contact of armature 10 and said armature, armature 16 and its working contact to lamp L' and battery. At armature 8 and its working contact relay 4 maintains ground on release conductor 2 thereby holding the switches operated by the calling party. The 100 operator again inserts the plug P into the jack J and converses with the calling party and extends the call in the same manner as previously described if the same is desired.

When the calling party hangs up after the 110 removal of the plug P slow acting relay 4 deenergizes after an interval and removes ground from the release trunk conductors 2 thereby allowing the switches operated by the calling party to release in the well known 115 manner.

In small telephone systems, as suggested in the first paragraphs of this specification, the operator may be required to perform special duties and accordingly it may so happen that the operator desires to be connected with a subscriber in the automatic exchange. The cord circuit CC is arranged so that it is unnecessary for the operator to plug in on an idle jack in order to complete a connection to a called subscriber. Assuming that the operator at the switchboard wishes to converse with some subscriber in the exchange, the operator will operate her dial key DK and dial the digits necessary to complete the con- 120 125 130

nection to the called subscriber. Responsive to the operation of the dial key DK a circuit is closed for relays 21 and 22 as follows: from ground through winding of relay 22, spring 33 of the dial key DK and its working contact, working contact of armature 37 and said armature, and winding of relay 21 to battery. Relay 21, upon energizing, closes a locking circuit for itself and relay 22 at armature 38 and its working contact through the spring 30 and its resting contact of the talking key TK. Relay 22, upon energizing, at armature 40 and its working contact, closes a circuit for the lower winding of polarized relay 23. Relay 23 will not energize over this circuit on account of it being an electro-polarized relay. Relay 22, at armature 40 and its resting contact, opens a point in the short circuit around itself so that it will be maintained energized when the dial key DK is restored to normal position. At armature 41 and its working contact, relay 22 prepares a bridge across the trunk conductors 45 and 46 for holding the automatic switches. At armatures 39 and 42, relay 22 bridges the calling device CD across the trunk conductors 45 and 46 thereby causing the operation of the lineswitch as has been previously explained.

30 The operator now dials the digits required to extend the call to the desired subscriber. In response to the digits dialled by the operator, the selector switch seized by the lineswitch LS and other switches respond to extend the talking connection. The last switch, being a connector switch, operates to complete the connection to the called subscriber's line; signals the called subscriber's line; and finally completes the talking connection when the called subscriber removes his receiver, as is well known in the art.

When the operator has completed dialling the desired subscriber's number, she restores the dial key DK to normal. In so doing, electro-polarized relay 23 is bridged across the conductors 45 and 46 in series with the retardation coil 24, relay 22 being in operated position. This bridge serves to hold the automatic switches in the established connection between the operator and the called subscriber in an operated position. Current now flows through the upper winding of relay 23 in series with the retardation coil 24 from a current supply from the connector switch. The direction of this current flow, however, is opposite to that necessary to cause the operation of relay 23; relay 23, therefore, remains inoperative at present. In response to the removal of the receiver of the called subscriber, a relay operation in the connector switch takes place, which reverses the current flow over the trunk conductor 45 and 46 and through the winding of relay 23. This results in the operation of relay 23 which opens the circuit of the lamp L² at armature 43. The

extinguishing of the lamp L² indicates to the operator that the called subscriber has answered. The operator, upon observing the extinguishing of the lamp L², throws the talk key TK to talking position thereby connecting her headset directly across the trunk conductors 45 and 46.

Responsive to the operation of talk key TK the locking circuit of relays 21 and 22 is opened at spring 30 and its resting contact. Relay 21 deenergizes but relay 22, however, is maintained energized over the following circuit: from ground through winding of relay 22, spring 30 of talk key TK and its working contact, armature 36 and its resting contact, resistance 35 to battery.

The operator and the called subscriber may now converse. When conversation is finished the operator restores the talk key TK to its normal position, whereby the circuit for relay 22 is opened at springs 30 of the talk key TK. When relay 22 deenergizes, said relay removes the bridge from across the conductors 45 and 46 thereby allowing the switches to release in the manner as previously explained.

Having described the invention, its utility and operation, what is considered new and is desired to have protected by Letters Patent will be set forth in the appended claims.

What is claimed is:

1. In a telephone system, a cord circuit extending to an automatic switch, a dialling key and a talking key in said cord circuit, means responsive to the operation of said dialling key for initiating the operation of said switch, means for holding the switch after the dialling key is restored, and means whereby the release of said switch is controlled by the subsequent operation of said talking key to its talking position and then to its normal position.

2. In a telephone system, a cord circuit terminating at one end in a lineswitch, a dialling key and a talking key in said cord circuit, a relay in said cord circuit having contacts for connecting said line switch to the talking conductors of said cord circuit, means responsive to the operation of said dial key for energizing said relay to close said contacts to initiate the operation of said lineswitch, means for maintaining said relay energized after said dial key is restored to normal, means for maintaining said relay energized after the talking key has been operated to talking position; and means responsive to the restoration of the talking key to normal position for de-energizing said relay whereby said line switch is restored to normal position.

3. In a telephone system, a cord circuit for use in connecting a calling party and a called party, a relay and a key individual to said cord circuit, a shunt circuit around said relay, contacts controlled by said key when actuated for opening said shunt circuit, a circuit for energizing said relay when the shunt

circuit is opened, and means for maintaining said relay energized during conversation between the calling and called parties.

4. In a telephone system, a single plug ended cord circuit terminating in one end in a plug and in the other end in outgoing trunk conductors, said conductors normally disconnected from the talking conductors of said cord circuit, a relay and a key individual to said cord circuit, a shunt circuit around said relay, contacts controlled by said key when actuated for opening said shunt circuit, a circuit for energizing said relay when the shunt circuit is opened, a calling device bridged across said trunk conductors responsive to the actuation of said key and relay, contacts in said shunt circuit opened by said relay whereby said relay is maintained energized after the key is restored, and a second bridge closed across said trunk conductors through contacts of said relay when the key is restored.

5. In a telephone system, a cord circuit at an operator's position, a dialling key, a talking key, a first relay, and a second relay in said cord circuit, means for energizing said relays responsive to the operation of said dialling key, means for maintaining said relays energized after the restoration of said dialling key, means for deenergizing said second relay and for maintaining said first relay energized responsive to the operation of said talking key, and means for deenergizing said first relay responsive to the restoration of said talking key.

25 6. In a telephone system, a cord circuit at
an operator's position, a dialling key, a talking
key, a first relay, and a second relay in
said cord circuit, means for energizing said
relays responsive to the operation of said
dialling key, means for maintaining said re-
lays energized after the restoration of said
dialling key, means for deenergizing said
second relay and for maintaining said first
relay energized responsive to the operation of
40 said talking key, means for deenergizing said
first relay responsive to the restoration of
said talking key, trunk circuits terminating
at said operator's position, and means for
45 rendering only said first relay responsive to
the operation of said dialling key and for
rendering the control of said first relay by
said talking key ineffective whenever said
50 cord circuit is connected with any one of said
trunk circuits.

55 7. In a telephone system, a cord circuit at an operator's position, a dialling key, a talking key, a first relay, and a second relay in said cord circuit, means including a local circuit in said cord circuit for energizing said 60 first and second relays in series responsive to the operation of said dialling key, contacts on said second relay for closing a second local circuit to maintain said relays energized after the restoration of said dialling key, means for 65 opening said second local circuit to deenergize

said second relay and for maintaining said first relay energized over a third local circuit responsive to the operation of said talking key, and means for opening said third local circuit to deenergize said first relay responsive to the restoration of said talking key. 70

8. In a telephone system, a cord circuit at an operator's position, a dialling key, a talking key, a first relay, and a second relay in said cord circuit, means including a local circuit in said cord circuit for energizing said first and second relays in series responsive to the operation of said dialling key, contacts on said second relay for closing a second local circuit to maintain said relays energized after the restoration of said dialling key, means for opening said second local circuit to deenergize said second relay and for maintaining said first relay energized over a third local circuit responsive to the operation of said talking key, means for opening said third local circuit to deenergize said first relay responsive to the restoration of said talking key, trunk circuits terminating at said operator's position, and means for opening said local circuits to render the same ineffective whenever said cord circuit is connected with any one of said trunk circuits.

9. In a telephone system, a trunk line terminating at one end in a plug ending cord circuit at an operator's position and terminating at the other end in an automatic switch, a relay in said trunk line, means for operating said relay only in case the operator initiates a call without inserting said plug in any jack at said position, and means for thereafter automatically operating said switch to use said trunk line as an outgoing trunk line. 95 100

10. In a telephone system, a trunk line terminating at one end in a plug ending cord circuit at an operator's position and terminating at the other end in an automatic switch, other trunk lines terminating at said position in jacks, said cord circuit used for answering calls extended over said other trunk lines and for extending such calls by way of said switch, a relay in said cord circuit, means for operating said relay only in case the operator at said position initiates a call herself without inserting said plug in any jack at said position, and means for thereafter automatically operating said switch to extend the connection responsive to the initiation of the operator's call. 105 110 115

11. In a telephone system, a trunk line terminating at one end in a plug ending cord circuit at an operator's position and terminating at the other end in an automatic switch, an operator's impulse sender at said position, a dial key in said cord circuit, a circuit controlled by said key for connecting said sender to said cord circuit while the sender remains in normal position, and means for operating said switch to extend a connection responsive to the operation of said dial key 130

whenever the operator initiates a call herself without inserting said plug of the cord circuit in any jack at said position and without operating said sender.

- 5 12. In a telephone system, a cord circuit terminating at one end in a plug and terminating at the other end in an automatic switch, means including the plug of said cord circuit for answering calls, means including an operator's impulse sender and said switch for extending such calls, and means including said sender for operating said switch to extend a connection without completing any connection to the plug of said cord circuit and without operating said sender.
- 10 13. In a telephone system, a cord circuit terminating in one end in an automatic switch, a talking key in said cord circuit, means for initiating the operation of said switch, means for holding the switch in operated position, and means whereby the release of said switch is controlled by the subsequent operation of said talking key to its talking position and then to its normal position.
- 15 14. In witness whereof, I hereunto subscribe my name this 21st day of October, A. D., 1926.

HARRY R. PARSHALL.
